DRY SPRAY EQUIPMENT

Charles William Britcher, Glen Ridge, N. J., assignor to Craig Corporation, a corporation of New York

Application April 30, 1948, Serial No. 24,402

6 Claims. (Cl. 118—308)

1

The present invention relates to spraying apparatus of the type used to spray dry, ground or powdered material and more especially to distribute such material uniformly over the surface to be sprayed.

The invention is an improvement over that of the prior patent to Herbert Cole No. 2,266,849 of December 23, 1941, and my prior Patent No. 2,375,766 of May 15, 1945, and while it has an important application in the graphic arts, it has a wider field of application for spraying ground or powdered material in other industries, among which are the following: rubber, coated fabrics, oil cloth, floor covering, plastic sheeting, insulating cloth, linoleum, food products, face brick, confectionery and baking, wall board and metallized paper.

It is among the objects of the invention to provide apparatus of the above type of simple and rugged construction which will not clog as long as the powder is kept dry and which assures uniform distribution under all conditions of operation.

Another object is to provide apparatus of the above type which may dispense entirely with driven parts and that is not likely to become deranged, the operation of which apparatus may readily and reliably be checked and adjusted, which lends itself to ease of cleaning, and to ease of replenishing, manually or automatically even during operation, and in which the apparatus including the powder distributing lines may readily be cleaned when operation is to be discontinued to avoid clogging during the period of idleness, especially where a hygroscopic powder is used.

Another object is to provide a device for apparatus of the above type that will permit free venting of the propulsive air and that will prevent excess powder from backing up in the spray discharge pipe with attendant blocking of the spray discharge vents, yet will prevent waste of such excess powder and the discharge thereof into the air or on the floor with resultant discomfort to the operator and that requires no moving parts, screens or other flow obstruction devices for its operation.

In the accompanying drawings in which are shown one or more of various possible embodiments of the several features of the invention,

Fig. 1 is a front elevational view showing the complete apparatus including the distributor pipe and spray tube,

Fig. 2 is a longitudinal sectional view taken through the supply tank and spray tank,

2

Fig. 3 is a fragmentary detail view in cross section taken along line 3—3 of Fig. 2,

Fig. 4 is a fragmentary detail view in cross section taken along line 4—4 of Fig. 2,

Fig. 4^a is a detail sectional view on a larger scale of the outlet head valve,

Fig. 5 is a longitudinal sectional view taken along line 5—5 of Fig. 1, and also showing the solenoid valve,

Fig. 6 is a fragmentary side elevational view taken along line 6—6 of Fig. 1,

Fig. 7 is a detail view on a larger scale showing a multiple outlet fitting,

Fig. 8 is a detail sectional view on a larger scale taken along line 8—8 of Fig. 1,

Fig. 9 is a fragmentary plan view of the spray tube taken along line 9—9 of Fig. 1, and showing one application of the device,

Fig. 10 is a fragmentary perspective view with parts broken away, showing another application of the device,

Fig. 11 is a side elevational view of still another application of the device, and

Fig. 12 is a side elevational view with parts broken away of another embodiment of the breather device.

In the accompanying drawings, Fig. 1 shows the various elements of the equipment which are mounted upon an upright panel 21 and from which is supplied the controlled spray for delivery to the distributor pipe 22 and thence to spray tube 23. The elements mounted on the panel include a spray tank 24 desirably comprising two cylindro-spherical cylinders 20 and 20' each having a flange 19 at the open end thereof which are clamped together by screws 25, a gasket 26 between the flanges providing an air tight seal. Tank 24 is supplied with compressed air from a suitable compressor (not shown) connected through an appropriate tube to inlet fitting or union U which delivers into an air filter 27 for removal of oil or other foreign matter. Filter 27 which is provided with a drain pet cock 28, communicates by way of pipe 29, through pressure regulator 31 which has a pressure gauge 32 associated therewith, and cross pipe 33 to shut off cock 34 which leads into the bottom of dehydrator tank 30. The latter desirably comprises two cylindro-spherical cylinders 40 and 40' each having a flange 18 at the open end thereof which are clamped together by screws 17, a gasket 16 between the flanges providing an air tight seal. Shut-off cock 34 has a mounting nipple 36 which is threaded into the bore 37 of a bushing 35 threaded into an opening

50 55

in the wall of the tank 30. The bore 37 of bushing 35 has a seat 38 therein on which a mesh screen disc 39 is placed, which is retained on its seat by a lock cap 41 threaded into said bore 37 and which has openings 42 therein affording communication to the interior of the dehydrator tank 30.

The bottom of the dehydrator tank 30 is also provided with a pet cock 43, the mounting nipple 44 of which is threaded into a hollow plug 45 threaded into an opening in the bottom of the dehydrator tank 30. The bore of plug 45 has a seat 46 on which is positioned a screen disc 47, held in place as by soldering.

The dehydrator tank 30 desirably is filled with a drying composition such as silica gel of the tell-tale type and is also desirably provided with a sight glass 48 comprising a bushing 49 threaded into an opening in the wall of the dehydrator tank 30 and having a glass disc 51 affixed by cementing or gluing on a seat 52 at the inner end of the bushing.

A bushing 53 threaded into an opening at the top of tank 30 has a tapped bore 54 reduced to form a seat 55 on which a mesh screen disc 56 is placed. The screen is retained on its seat by a lock sleeve 57 threaded into bore 54 and which has lateral openings 58 affording communication with the interior of the dehydrator tank 30.

From the top of tank 30 a pipe 59 threaded into bushing 53, leads into solenoid valve 61 which as it is conventional in construction will not be described in detail.

Valve 61 which when deenergized is in closed position, is connected by cross conduit 62 and pipe 63 to pressure regulator 64 the latter having a pressure gauge 65 associated therewith. From regulator 64, pipe 66 leads to needle valve 67 which has a nipple 68 threaded into the lower end of the bore 69 of air inlet plug 71. The latter is threaded into an opening at the bottom of spray tank 24 which also has a drain plug 72 therein.

In order to form a cloud of powder in the tank, stationary means are provided to direct a stream or jet of air into the powder in such manner as to violently agitate the same. Desirably such means are in communication with the air inlet 71 and have one or more lateral outlets above the level of the powder in the tank.

In a preferred embodiment herein shown, a vertical air tube 73 is provided, extending the major part of the height of said tank and threaded at its lower end 74 into the upper end of bore 69 of inlet plug 71.

The upper end of tube 73 has a T-fitting 75 threaded thereon, each laterally extending arm 76 of which has threaded therein a substantially L-shaped air agitator tube 77, the downwardly turned portion 78 respectively of each of which is provided with a nozzle 79 and is curved inwardly, said portions 78 each being inclined from the vertical. Preferably the curvature of portions 78 is such that each nozzle 79, which has an aperture therein of approximately .067 inch, will direct a jet of air at a downward angle of about 38 to 40 degrees across radii of the tank toward the opposing surface of the wall thereof and as the nozzles 79 are displaced from the center of the tank, the jet of air will strike the wall at such an angle as to be deflected downwardly along such wall in an oblique path for maximum mixture of the contents of the tank.

Although the agitator tubes 77, as shown, will whirl the air in a clockwise direction, it is of course to be understood that they could be ar-

ranged to whirl the air in a counterclockwise direction, the mixing action being the same.

The spray tank 24 is provided with a sight glass 81 identical to sight glass 48 in the dehydrator tank 30, comprising as it does a bushing 82 threaded into an opening in the wall of the spray tank 24 and having a glass disc 83 affixed as by cementing or gluing on a seat 84 at the inner end of the bushing.

In order that the interior of the spray tank may be viewable through sight glass 81, the upper part of the spray tank is desirably equipped with an electric lamp 85 threaded into a socket 86 affixed in an opening in the tank 24. The lamp 85 is constantly illuminated while the device is operating so that the powder cloud set up in the spray tank 24 may be inspected to check on the operation of the machine.

To obviate the obscuration of the sight 81 from the heavy deposit of powder thereon incurred in operation of the machine, cleaning means are provided for the sight. Such means comprises a rod 89 extending through a bearing 91 threaded in an opening in the wall of spray tank 24 below sight 81 thereof. The portion of rod 89 extending inside the tank is upwardly bent as at 92 with a flat angle end 93 parallel to the face of sight glass 83. A brush 94 is secured to angle end 93 by screws 90 and rubs over glass 83 when rod 89 is rotated by a knob 95 affixed to the outer exposed end of rod 89. A pin 96 transversely through an opening in rod 89 adjacent the inner end of bearing 91 coats with a pair of pins 97 affixed on the inner end of the bearing and extending laterally inward therefrom to limit the rotation of rod 89.

Mounted at the top of the spray tank 24 is an outlet head 109 comprising a valve stem bearing 111, a valve top 112 and a valve base 113 retained together by screws 110 extending therethrough into a threaded opening 104 in the top of the spray tank. A stop plate 154 is also provided secured to valve stem bearing 111 by screw 110, a tight seal being maintained between the stop plate 154 and the valve stem bearing 111 by gasket 150. Base 113 has an internally threaded stem 114 extending slightly into the interior of spray tank 24 and an inlet sleeve 115 is threaded into stem 114. Sleeve 115 has a bore 116 leading into stem 114 and a plurality of openings 117 are provided extending through sleeve 115 into bore 116 thereof.

The valve stem bearing 111 has a bore 119 extending vertically therethrough, countersunk at both ends thereof as at 121 and 122, and a transverse bore 123 extends therethrough and intersects said vertical bore 119. An annular recess 125 is provided in valve stem bearing 111 coaxial with the narrow end of bore 123 and of larger diameter than such end. A tapered feed valve stem 126 fits into the correspondingly tapered bore 123 and has a reduced threaded end 127 which extends beyond recess 125. A laterally extending pin 128 is affixed in the shoulder 129 formed by reduced end 127 and fits into a corresponding opening 132 in a valve stem washer 131 positioned in recess 125 and retained therein by a nut 133 threaded on end 127, the nut serving to retain the valve stem 126 in bore 123.

Valve stem 126 has a bore 135 extending transversely therethrough and a transverse bore 136 at right angles to bore 135. Valve bearing 111 is also provided with a transverse bore 137 extending into bore 123 thereof and having a socket 138 in which is threaded the nipple end of a cross pipe 139 carrying a T-coupling 149 at its

other end. The lower arm of the coupling 149 is connected by pipe 151 to T-coupling 152 which connects pipes 63 and pressure regulator 64.

The bores in valve stem 126 are so positioned that when the stem is turned by handle 153 thereof to its extreme left position as shown in Fig. 1, as limited by the arms 155 of stop plate 154 which straddle handle 153, the valve stem will be in the spray position with bore 135 thereof aligned with bore 119 of the valve stem bearing 111.

In the extreme right hand position of handle 153, bore 135 will be aligned with bore 131 and bore 136 will be aligned with the upper portion of bore 119 thus cutting off communication with the spray tank 24 and permitting air to be blown through the outlet head 109 in the manner hereinafter described.

Valve top 112 has a bore 157 therethrough countersunk on its bottom as at 158 and in juxtaposition to the countersunk portion 122 to form a mixing chamber to facilitate mixing of air and powder. A booster fitting 161 which is preferably cast from bronze, has a vertical bore 162 therethrough, threaded at its lower end on a nipple 159 in turn threaded into the bore 151 of the valve top 112. Fitting 161 also has a bore 163 extending at an angle of approximately 20 degrees into bore 162 near the upper end of the fitting and has a threaded lower end 164 to which is connected a bushing 165 holding a tube 166, one end 167 of which extends through bushing 164 and bore 163 into bore 162 and the other end 170 of which is connected to nipple 168 of booster needle valve 169 connected to the upper end of T-coupling 149.

Threaded on the upper end of the booster fitting 161 is dividing head 171 which, as shown in Fig. 7, illustratively has two openings 172 therein, in each of which is desirably threaded a double powder feed 173, provided with shut-off hand cocks 174 for each of the outlet couplings 175 thereof, to turn on and off the air and powder stream. In the embodiment of Fig. 1 only one outlet coupling is utilized, the others being shut off by hand cocks 174.

A spray tube 23 desirably extending horizontally between brackets 178 and directly over, or, if desired, under the usual horizontal surface 180 to be sprayed, is fed through distributor pipe 22 from the respective open outlet coupling 175. Distributor pipe 22 leads into a Y fitting 176 having an air relief valve 177 which is connected to the feed or inlet end of spray tube 23.

In a preferred embodiment of the spray tube 23 shown in Figs. 1 and 9, the length thereof is corrugated, as shown, along the effective width of the surface to be coated. These corrugations are desirably uniform in length and height. The corrugations are preferably of such height that the crests thereof in the wall of the bore are substantially aligned with the troughs thereof at the diametrically opposite wall portion as shown by dot and dash lines in Fig. 9.

The spray tube 23 has spray apertures 179 that are equidistant and at one side of the tube 23 and in linear alignment. They are preferably not at the very trough of the corrugations, but each aperture is spaced slightly behind said trough, that is, somewhat farther from the tube outlet than is the bottom of the trough. The spray apertures are preferably inclined so that they slope downward from the bore of the spray tube and outward in direction opposed to that of the air flow therethrough.

While the dimensions of the spray tube and its apertures may be varied to suit different requirements, it has been found from experience that a particularly desirable arrangement, suitable in a wide variety of uses, consists of a tube of $\frac{1}{4}$ inch bore with a distance between successive troughs of about 2 inches, preferably $1\frac{1}{32}$ inches.

Inasmuch as the air pressure is greatest at the feed end of the spray tube and will decrease along the length thereof due to its escape from the aperture therein, there will be a tendency for the powder to rush past the aperture closest to the feed end. In order that the output of powder from each aperture be substantially the same, the spray apertures are desirably graduated in size, being larger at the feed or inlet end of the spray tube, illustratively .065 inch in diameter and decreasing to approximately .031 inch. Thus in a spray tube having a spraying length of 60 inches, beginning at the feed end of the tube, there will be ten .065 inch apertures, thirteen .036 inch apertures and eight .031 inch apertures. Thus as the powder rushes by the larger apertures at the feed end of the spray tube substantially the same quantity will escape therefrom as from the smaller apertures at the opposite end of the spray tube.

Each of the apertures 179 is preferably $\frac{3}{16}$ inch in advance of the troughs and is bored into the tube after the same has been corrugated. Preferably the axis of the tube is inclined slightly to an angle of about $4\frac{1}{4}$ degrees for such drilling so that the vertically directed drills will bore the aperture at a downward inclination.

In order to prevent backing up of powder and air in the spray tube which might clog the same, a breather 180 is provided the operation of which will be hereinafter described in detail. The breather comprises a top cap 181 threaded on the open end of a pipe 182 connected to the end of the spray tube 23. An outer shell 183 is threaded into cap 181 so as to hang downward therefrom. A bottom cap 184 having a tube 185 threaded into an opening 186 therein, is threaded on the bottom end of shell 183. The tube is of such length as to extend upward to nearly the opening 160 in top cap 181 and is plugged at its upper end as at 187 and provided with an aperture 188 through the wall thereof extending into the bore of the tube 185.

In order to energize the solenoid valve 61 and the lamp 85 during operation of the device, they are connected in parallel with main 205 which has a switch 206 in circuit therewith. A mercury switch 207 is also provided under control of the more or less remote mechanism when the spraying is to be done. Thus for example, if the surface to be sprayed should stop moving, the mercury switch 207 would be actuated to cut off the power to the solenoid valve 61 and cause the latter to close and also turn off the lamp 85.

Upon closing of the switches 206 and 207, solenoid valve 61 will be energized and open and the lamp 85 will be illuminated. Compressed air will pass from the source of pneumatic pressure (not shown) to inlet fitting U which discharges into air filter 27 where the air will be cleaned and then pass through pipe 29 and pressure regulator 31 normally set at 50 pounds as indicated on gauge 32. From the pressure regulator the air will pass through cross pipe 33 and shut-off cock 34 through mesh screen 39 which prevents any debris or foreign matter passing therethrough, into the bottom of the dehydrator tank 30.

The air after being dried in its passage through the silica gel in the dehydrator tank will pass through mesh screen 56 to remove any particles therein and then pass through pipe 59 and the open solenoid valve 61, through cross conduit 62 and pipe 63 to pressure reducing valve 64 where the pressure is set to from 2 to 5 pounds as indicated on gauge 65. The air then passes through pipe 66, open needle valve 67 to the spray tank by way of the bore 69 of air inlet plug 71 and thence through air tube 73 and out of apertures 79 of the agitator tubes 77, thus delivering two currents of air which will be whirled in a clockwise direction at a downward angle, as shown, of about 36 to 40 degrees.

In ordinary spraying, as in the graphic art industry for example, the needle valve 67 is kept open at all times, but in some applications where it is desired to increase the pressure of the air entering the spray tank 24 without increasing its volume the size of the orifice in the needle valve 67 can be slightly reduced.

As a slight pressure, approximately 2 to 5 pounds will be built up in tank 24, when valve handle 153 is in spray position with bore 119 aligned with bore 135, some of the powder from the cloud formed by the whirling air currents set up in the tank 24 through pipes 78 will be forced through the outlet head 109.

In order to increase the intensity and quantity of the air and powder stream from outlet head 109, needle valve 169 is manually opened to permit a jet of air under the initial relatively high pressure of approximately 50 pounds to be forced through tube 166 into bore 163 of booster fitting 161 and thence into bore 162. The path of the air is from inlet fitting U, air filter 21, pipe 29, pressure regulator 31, pipe 33, shut-off cock 34, dehydrator tank 38, pipe 59, solenoid valve 61, pipes 62, 63 and 151, needle valve 169 and into tube 166.

The movement of the air will exert an effective suction on tank 24 to draw additional particles of powder therefrom through bore 118 and aperture 117 of sleeve 115. It is of course apparent that the greater the air pressure or velocity of the air through bore 163 of the booster fitting the greater will be the amount and intensity of the powder stream propelled through the outlet couplings 175 and the distributor tube 22 to the spray tube 23 wherefrom it is sprayed on the surface being treated.

It is to be noted that in passing through the spray tube 23, the obstructions imposed by the corrugations therein will intercept some of the powder entrained with the air forced through the feed end of the tube 23 while some will be blown through the apertures 179 for the spraying action desired. The location and size of the spray apertures hereinbefore set forth brings about an effective and uniform spray therethrough, both through those near the inlet of the spray tube and those remote from the inlet. It is to be further noted also that were the obstructions imposed by the corrugations omitted, the spray would be far from uniform, as some holes would deliver considerably more powder than others. If the corrugations were of much greater amplitude than shown, uniformity would also be impaired and the same is true if they were of lesser amplitude, in which case there would be a tendency for the apertures remote from the inlet to feed more powder than those in advance thereof.

By the arrangement set forth, in which the crests of the corrugated pipe bore are aligned

with the diametrically opposite troughs of such bore, it has been found that the resistance imposed in advance of each spray aperture is exactly right for bringing about the uniformity of distribution. The disposition of the spray aperture 179 slightly beyond the bottom of the trough and in the direction set forth, assures a uniform symmetrical spray where the location of such aperture elsewhere or at a different angle would lead to a spray deflected either to the right or to the left from that shown and thus render the distribution less uniform.

It will be understood that while in general the spray apertures are at the forward side of the spray tube, the corrugations of which lie in a horizontal plane, as best shown in Figs. 1 and 9, the plane of the corrugation may for certain applications be tilted downward or, in some cases, it may be tilted upward to the desired angle for spraying the underface of a sheet or plate passed thereabove. The length of the spray tube of the present invention may be extended obliquely or even vertically for certain special applications as, for instance, the coating of a wall or a silo, and the distribution of powder is found to be thoroughly uniform in any of such applications.

It will also be understood that two or more of the spray tubes may be arranged in parallel and in slightly cascaded relation for great precision of powder distribution. In such case the outlet head of the device would be equipped with a sufficient number of outlet couplings for distributor tubes to supply all of such spray tubes.

When the air and entrained powder that is not discharged through the spray apertures 179 reaches the end of the spray tube 23, they will enter the outer shell 183 of the vertical breather device 180 through tube 182. As the air pressure during its passage through the distributor pipe 22 and spray tube 23 has decreased from approximately 2 to 5 pounds in the tank 24 to but a negligible amount when it enters shell 183, the powder particles will drop to the bottom thereof which is sealed by bottom cap 186 while the air will escape through lateral aperture 188 in tube 185 and out of opening 186 in bottom cap 186. As aperture 188 is near the top of the breather 180 normally no powder will escape therethrough. However, when the powder level in the shell rises up to aperture 188 a mist of powder will be ejected from opening 186 in the bottom of the breather instead of clean air. This will indicate that it is time to empty the shell which is done by unscrewing the shell from its top cap. The powder thus emptied may be salvaged for re-use.

Throughout the operation of the spray apparatus the operator may inspect the efficiency of the powder cloud and determine the level of powder in the spray tank through the sight glass to assure best operation.

When no further spraying is required, it is desirable to clear the spray tube and distributor tube of powder remaining therein as exposure of the latter to the atmosphere for any length of time may result in clogging and contamination, especially if the powder be of hygroscopic character. To this end, valve handle 153 in the outlet head is moved from spray position to blowout position. Valve stem 126 will thus be turned in its bore 123 so that communication to the spray tank 24 will be sealed and bore 135 of stem 126 will be aligned with bore 137 of valve fitting 111 to provide a passage for the compressed air which is under a relatively high pressure of 50 pounds from the compressor (not

shown) which is connected to union **U**. The path of the air is from air filter **27**, pipe **29**, through pressure regulator **31** and cross pipe **33** into dehydrator tank **30**. From the outlet end of said tank **30** through pipe **59**, valve **61**, cross pipe **62**, pipes **63**, **151** and **139**, through bores **137**, **135** and **136** into bore **162** of booster fitting **161**, then through distributor pipe **22** and spray tube **23**. Thus the distributor pipe and spray tube will be blown clear of powder, forcing such powder into the breather device **180**. Switch **206** may then be opened and valve handle **153** reset to spray position to ready the device for subsequent operation.

After repeated use of the device, the silicon gel will have absorbed sufficient water so that the dehydrator tank **30** no longer functions properly. To check on this it is merely necessary for the operator periodically to glance through sight glass **48**.

When the gel is blue, the air passing therethrough toward the upper end of the dehydrator tank is dry and the dehydrator is functioning properly. When the gel is pink or salmon in color, it is saturated to about 40 per cent relative humidity and should be replaced with a refill of activated (blue) gel. Removal of the bushing **45** allows the saturated gel to drain from the dehydrator tank. When the bushing **45** has been replaced with shut-off cock **43** closed, the sight glass **48** is removed for refilling the dehydrator.

In order to replenish the supply of powder in the spray tank **24**, a powder supply tank **99** is desirably mounted adjacent to and at a higher level than spray tank **24**, by means of a bracket **101** connected to the bottom of the powder tank **99** by screw **102** and to the side wall of the spray tank **24** by screws **103**. The top of the powder supply tank is closed by a cover plate **108** removably threaded thereon at **107**. Communication is established between the powder supply tank **99** and the spray tank **24** by means of a nipple **105** having a valve **106** therein. To replenish the spray tank the powder supply valve **106** is opened, allowing the compressed air from the spray tank **24** to pass into supply tank **99** which had previously been filled with powder. Inasmuch as tank **99** has no outlet except that provided by valve **106** a pressure will be built up therein.

In order to break the circuit to the solenoid valve **61** thereby causing the latter to close and shut off the air supply to the spray tank **24**, a switch button **208** is provided in series with said solenoid valve **61**. With the button depressed and the valve deenergized and closed, the air in the spray tank **24** will thereupon escape through open outlet head **109** causing the pressure in tank **24** to fall.

The greater pneumatic pressure now existing in supply tank **99** will effect expulsion of powder therefrom through open valve **106** into spray tank **24**. By alternately pressing and releasing the button **208** the process of transferring powder from the supply tank to the spray tank is continued until the latter is half filled as seen through sight glass **81**. Valve **106** is thereupon closed. This procedure enables the operator to replenish the spray tank with powder from the supply tank **99** even while the spray is operating. However in cases where it is desired to feed large quantities of powder the above method of supplying the spray tank **24** would require too much manual attention.

To remedy this, for industrial dusting operations, an automatic timer **209** is provided shown in dashes in Fig. 1. This timer, the construction of which is conventional and which per se forms no part of this invention, replaces switch **208** in the circuit and hence is in series with the solenoid valve **61**. The electric timer **209** is set, automatically to open and close the solenoid valve approximately $\frac{1}{2}$ second out of every 30 seconds to control the feeding of powder into the spray tank **24** as above described, when normally closed button **208** is pressed to open the circuit to valve **61**.

In the use of the automatic timer **209**, valve **106** is opened sufficiently to admit powder into the spray tank **24** each 30 seconds, at substantially the rate of use thereof, thereby to maintain a substantial constant level of powder in the spray tank.

In the embodiment of the breather device **180** shown in Fig. 12, a top cap **181'** is provided, threaded on the open end of pipe **182** connected to the end of the spray tube **23**. A cylindrical container **183'** is threaded into cap **181'** so as to hang downwardly therefrom, and an air relief valve **200** is positioned on cap **181'** in communication with the interior of container **183'**.

Thus when the device is in use, the air and entrained powder that is not discharged through the spray apertures **179**, when they reach the end of the spray tube **23**, will enter the container **183'** of the vertical breather device **180'** through tube **182**. As the air pressure during its passage through the distributor pipe **22** and spray tube **23** has decreased as has been heretofore described, the powder will fall to the sealed bottom of the container **183'** and remain therein while the air will escape through air relief valve **200**. As the valve is near the top of the breather **180'**, normally no powder will escape therethrough. However, when the powder level in the container rises to fill the same, a mist of powder will be ejected from the air relief valve instead of clean air. This will indicate that it is time to empty the container **183'** which is done by unscrewing the latter from the top cap **181'**. The powder thus emptied may be salvaged for re-use.

In Fig. 10 the device herein is shown as applied to a dust chamber **191** for spraying material in motion. In this application the four outlet couplings **175** are utilized, each connected respectively by a distributor tube **192** to an ejector pipe **193** slidably mounted in a bearing bushing **194** affixed to the side wall **195** of the dust chamber **191**. The ejector pipes **193** are mounted in pairs of each side wall **195** so as to spray powder over the web of material **196** which moves longitudinally through the chamber **191**. The slideable pipes may be adjusted laterally to accommodate for different widths of web.

In Fig. 11 the device is shown as applied to a machine **197** for manufacturing extruded tubing illustratively of rubber. As this machine itself is conventional and forms per se no part of this invention, it will not be described in detail.

One of the outlet couplings **175** is connected by distributor tube **198** to an ejector pipe **199**, the nozzle end **201** of which extends into the bore of the extruded tubing as it emerges from the machine **197**, and dusts the interior of such tube, thereby preventing the walls of the same from sticking together if they should contact each other.

It is of course to be understood that the applications of the device herein shown are merely

illustrative of the many uses to which it can be put and are not intended to limit such uses in any way.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A dry powder spray equipment comprising a powder spray tank having an outlet and an inlet, means for delivering compressed air into said inlet, one or more fixed nozzles in said tank connected to said inlet and each positioned to direct a jet of air across radii of said tank and downward into the powder in said tank at an angle of less than 90 degrees, to whirl said air in an oblique path thereby to stir up a cloud of powder in said tank and means associated with said outlet for creating a suction in said tank whereby powder may be entrained from such cloud for delivery to the surface to be sprayed.

2. A dry powder spray equipment comprising a tank for dry powder, having an outlet at the top thereof, an upstanding tube in said tank rising through such powder and connected at its lower end to a source of pneumatic pressure, fixed air agitator tubes affixed to the top of said first named tube and extending substantially laterally therefrom, each of said air agitator tubes having a curved, downwardly extending portion having a nozzle at the end thereof, each of said downwardly extending portions being tilted from the vertical so that said nozzles may direct jets of air across radii of said tank downward toward the bottom of the latter at an angle of less than 90 degrees to whirl said air in an oblique path, thereby to stir up a cloud of powder in said tank and means associated with said outlet for creating a suction in said tank whereby powder may be entrained from such cloud for delivery to the surface to be sprayed.

3. Powder spraying apparatus comprising a tank for powder, means connecting said tank to a source of compressed air, means in said tank actuated by said compressed air for stirring up a cloud of powder in the upper part of said tank, an outlet head on said tank and normally in communication therewith, means connecting such source of compressed air directly to said outlet head, and a feed valve in said outlet head shutting off communication from the tank therebelow and directing the air blast through said outlet head.

4. A dry powder spray equipment comprising a powder spray tank having an outlet head at the top thereof and an air inlet at the bottom thereof, a tube connected to said air inlet and extending upwardly into said tank, means for delivering compressed air through said tube, means to dry such compressed air before delivery to said tube, air agitator tubes affixed to the top of said first named tube and extending laterally therefrom, each of said air agitator tubes having a curved, downwardly extending portion having a nozzle at the end thereof, through which the

compressed air delivered through said air agitator tubes may be expelled thereby stirring up a cloud of powder in the tank, and means associated with the outlet head for entraining powder from such cloud for delivery to the surface to be sprayed.

5. Powder spraying apparatus of the character described comprising a tank for dry powder having an inlet thereto at the lower end thereof, means connecting a source of compressed air to said inlet, means to dry such compressed air before passage thereof through said inlet, an outlet head at the top of said tank and normally in communication therewith, a tube extending upwardly in said tank from the lower end thereof and connected to said inlet, air agitator tubes affixed to the top of said last named tube and extending laterally therefrom, each of said agitator tubes having a nozzle, the compressed air delivered through said nozzles thereby generating a cloud of powder in said tank and building up pressure therein to force powder from such cloud in said tank through said outlet, means connecting such source of compressed air directly to said outlet head and normally not in communication therewith, and a valve in said outlet head to close off communication from said tank and provide communication from said last named means thereto.

6. Powder spraying apparatus comprising a tank for powder, means connecting said tank to a source of compressed air, means in said tank actuated by such compressed air for stirring up a cloud of powder in the upper part of said tank, an outlet head on said tank and normally in communication therewith, means connecting said source of compressed air directly to said outlet head, a feed valve in said outlet head shutting off communication from the tank therebelow and directing the air blast through said outlet head, a lamp in said tank near said outlet head, a sight glass mounted on said tank through which the illuminated interior of the tank may be viewed and means to clean the inner face of said sight glass, said means comprising a rod extending through an opening in said tank and journaled therein, said rod having a brush affixed to its inner end in juxtaposition to the inner face of said sight glass whereby when the extending end of said rod is rotated, said brush will sweep over said glass to clean the latter.

CHARLES WILLIAM BRITCHER.
